FIG. 1.

FIG. 2.

FIG. 3.

Inventor
William H. Peirce

By his Attorney Albert M. Austin

UNITED STATES PATENT OFFICE

WILLIAM H. PEIRCE, OF BALTIMORE, MARYLAND, ASSIGNOR TO AMERICAN SMELTING & REFINING COMPANY, OF NEW YORK, N. Y., A CORPORATION OF NEW JERSEY

LADLE

Application filed May 10, 1928. Serial No. 276,552.

This invention relates to a process and apparatus for casting metals and more particularly to a pouring ladle having means associated therewith for completely filling a mould to a uniform thickness.

In pouring metal into moulds of intricate shapes, such as, for example, an anode for an electrolytic cell which comprises a body portion and a pair of outwardly extending lugs by means of which the anode is supported, difficulty has been experienced in completely filling the various parts of the mould to a uniform level before an undesired amount of cooling has taken place. It is commonly desirable to use a mould formed of material which is a good conductor of heat and also to pour the metal at a temperature not greatly above its melting point. The mould in this case quickly absorbs the excess heat of the metal, thereby causing the same to rapidly solidify. The metal may become viscous before it reaches the portions of the mould farthest away from the point of pouring with the result that these portions of the completed casting are thinner than the remainder thereof.

The present invention provides a new and improved pouring means whereby the metal is rapidly directed toward the remote recesses of the mould and is caused to fill the entire mould to a uniform thickness. The apparatus used for the delivery of the metal from its original source to the mould has been styled a pouring ladle but is intended to include any equivalent device such as a spoon or a runner. The ladle is so designed that the molten metal flows in a plurality of directions which are determined by the peculiarities of the particular casting involved. The invention further provides for varying the distribution of the metal during the pouring operation. This is accomplished by providing means for changing the direction of pouring in accordance with the angle of inclination of the ladle and variably tipping the ladle after a portion of the metal has been removed therefrom.

The invention also consists in certain new and original features of construction and

combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a plan view of the pouring ladle and mould, showing the relative positions of the parts.

Fig. 2 is a section taken on the line 2—2 of Fig. 1 showing the position of the molten metal at the initiation of the pouring operation, and

Fig. 3 is a sectional view showing the ladle tilted and illustrating the distribution of the molten metal.

Like reference characters denote like parts in the several figures of the drawings.

In the following description and in the claims parts will be identified by specific names for convenience, but they are intended to be as generic in their application to similar parts as the art will permit.

Referring to the drawings more in detail, the invention is shown as comprising a pouring ladle 10 formed with a dished portion 11 which is adapted to receive molten metal 12 from any suitable source. The ladle is provided with an extended spout 13 by means of which the metal is directed onto a mould 14. The end of spout 13 is provided with an aperture 15 through which the molten metal is passed onto the mould. Adjacent said aperture and at the extreme end of spout 13 is provided a downwardly extending and rearwardly inclined flange 16 for a purpose to be set forth.

Mould 14 has been shown by way of example as of a suitable shape for the casting of electrolytic anodes which comprise a body portion 17 and outwardly extending lugs 18. The pouring ladle 10 is so located that aperture 15 therein lies over the central portion of mould 14 whereby the molten metal is in-

roduced into the mould centrally thereof and may spread substantially equally in all directions.

During the pouring operation, the ladle is commonly filled to a sufficiently high level so that the metal flows through aperture 15 onto mould 14 while the ladle is in a substantially horizontal position as shown in Fig. 2. The metal striking the cold surface of the mould spreads out in all directions and at the same time is rapidly cooled to its melting point.

At a time determined by the operator, when the metal has become so viscous that it will be unable to properly fill the various recesses to form lugs 18, the ladle is tilted to the position shown in Fig. 3. The metal is then deflected so that a larger portion thereof is directed toward said recesses whereby they are filled to the same depth as the remainder of the mould. It has been found that by tilting the pouring ladle at the correct time with respect to the cooling gradient of the metal, the mould may be filled to a uniform depth throughout its entire area.

In carrying on this process it is essential to so form rearwardly inclined flange 16 with respect to aperture 15 that the necessary portion of the metal is deflected toward the remote corners of the mould while at the same time the remainder of the metal is allowed to spread out over the entire surface thereof. The relationship between the quantities of metal flowing in the various directions depends upon the size and location of the recesses of the mold and upon the rapidity with which the metal is allowed to cool to the point at which it becomes viscous. It has been found that by suitably selecting the mechanical dimensions of the mold and controlling the tilting thereof, pouring of metallic anodes has been greatly simplified and a more uniform product has been obtained.

Although the invention has been shown and described as applying to a particular type of mould, it is obviously not limited thereto but is equally applicable to casting operations in general where it is desired to control the distribution of the metal in a predetermined manner.

What is claimed is:

1. A pouring ladle for moulding operations having an outwardly extending spout, means in said spout for permitting metal to be discharged vertically and means associated with said spout whereby when said ladle is tilted a portion of the poured metal is directed rearwardly of said spout.
2. In a pouring ladle for casting operations a forwardly extended spout having an aperture therein through which molten metal may pass and a downwardly extending flange located forwardly of said aperture and adapted to contact with the metal passing there-

through for changing the direction of flow thereof.

3. A pouring ladle comprising a body portion adapted to receive fluid material, a spout having means associated therewith for discharging said material and a downwardly extending flange associated with said spout and adapted to contact with the discharged material for directing a portion thereof in a direction opposed to the direction of flow in said spout.

4. In combination with a pouring ladle, an outwardly extending spout having an aperture therein for the discharge of fluid material, a downwardly extending and rearwardly inclined flange located adjacent said aperture and adapted to contact with the discharged fluid when said ladle is tilted to a predetermined position.

5. In combination with a mould having remote recesses therein, a pouring ladle, means associated with said ladle for normally discharging the casting metal centrally of said mould and means for directing a portion of said metal toward said recesses when the viscosity thereof has been increased by cooling.

In testimony whereof I have hereunto set my hand.

WILLIAM H. PEIRCE.
